UNITED STATES PATENT OFFICE.

WILLIAM M. HAVER, OF CAMBRIDGE, OHIO.

RAIL JOINT OR COUPLING.

1,205,529.

Specification of Letters Patent. Patented Nov. 21, 1916.

Application filed April 4, 1916. Serial No. 88,851.

To all whom it may concern:

Be it known that I, WILLIAM M. HAVER, a citizen of the United States, residing at Cambridge, in the county of Guernsey and State of Ohio, have invented certain new and useful Improvements in Rail Joints or Couplings, of which the following is a specification.

This invention relates to certain new and useful improvements in rail couplers or joints, and it has for its object among others to provide an improved rail joint or coupler in which all bolts, nuts, washers, fish plates and angle bars are dispensed with, as well as eliminating the requirement for any holes whatever in either the rail or the coupler. I provide a coupler which will prevent the rail from breaking down at the joint and which will also prevent one rail from spreading farther than the other, thus avoiding the leaving of a space for the flange of the wheel to catch in.

The present invention has for a further object the production of a coupler which shall be capable of manufacture at small cost, durable and efficient and reliable in its operation, and easily applied and renewed if occasion require.

It has for a further object to provide means whereby the coupler will creep with the rails, as well as protecting the wedges by covering them with a projecting portion or flange of the coupler.

Other objects and advantages of the invention will hereinafter appear, and the novel features thereof will be specifically pointed out in the appended claims.

The invention is clearly illustrated in the accompanying drawings, which, with the numerals of reference marked thereon, form a part of this specification, and in which—

Figure 1 is a top plan view, with parts broken away and a part in section. Fig. 2 is a vertical cross section on the line 2—2 of Fig. 1. Fig. 3 is a perspective view of the coupler body. Fig. 4 shows in perspective a pair of wedges. Fig. 5 is a perspective view of a pin for use in connection with the wedges. Fig. 6 is a cross section, on an enlarged scale, as on the line 6—6 of Fig. 1.

Like numerals of reference indicate like parts throughout the several views.

Referring to the drawing 1 and 2 indicate the abutting ends of two rails. 3 designates the joint plate or coupler body; it is formed with a base portion on which the base of the

rail rests as seen in Fig. 2, and along one edge with the inwardly-extending flange 4, providing a groove 5 to receive one edge of the base flange of the rail, while along the opposite side there is a groove 6 to receive the opposite edge of the base flange of the rail, as seen in Fig. 2, the flange portion 7 resting upon the top of the said flange of the rail, as shown. From the inner end of this flange 7 there extends the vertical portion 8 terminating in the horizontal flange 9 which forms a protecting cap for the wedges, soon to be described. This provides a space or chamber 10 between the vertical wall 8, the cap portion 9 and the adjacent web 11 of the rail as will be readily understood from Figs. 2 and 3.

12 are wedges which in use are employed in pairs as shown, and which upon their adjacent faces, near each end, are provided with grooves 13, as seen best in Figs. 1 and 4 to receive the pins as will soon be set forth. These pins 14, as seen best in Figs. 5 and 6, are slightly bulged or enlarged near their lower ends as seen at 15, for a purpose which will hereinafter be made apparent.

In practice, the coupler is applied as shown, and then the wedges 12 are driven into the space 10 and when in place the pins 14 are driven into the grooves 13 of opposed wedges, when the wedges may be driven a little farther endwise if necessary and the wedges and pins covered and protected by the horizontal flange 9 of the coupler as shown in Fig. 2. These pins keep the wedges from working loose and when the pins are made of the shape shown in Figs. 5 and 6 the wedges will close in slightly as the pins are driven to the bottoms of the wedges and thus a more secure holding of the pins is assured. It is to be understood that the wedges 12 are moved relatively to each other after being inserted in the chamber 10, to perform a wedge action.

The pins 14 may be provided with a hole therethrough as seen in Fig. 5, if desired, to receive a tool for pulling the pin.

17 and 18 are pins passed through the openings 19 and 20 in the portions 4 and 7 respectively of the coupler and through coincident openings in the opposite sides of the base flange of the coupler and into the space between the adjoining ends of the rails 1 and 2 as seen in Figs. 1 and 2, so that the coupler will creep with the rails. These pins may be easily replaced should they be-

ccme worn. They may be secured in position in any suitable way, preferably by being threaded and having nuts upon said threads; cotter pins 21 also may be employed, as 5 seen in Fig. 2.

Should the wedges work out the stay flanges 4 and 7 will serve to effectually hold the rails in place. The wedges may be easily driven back into place. The vertical portion 10 8 of the coupler may extend to any desired height. The wedges are long and slim and are preferably of such length as to extend at both ends beyond the ends of the coupler before they are driven into place and they 15 may extend at both ends after they have been driven home.

The coupler may be adjusted as follows:— Pull the pins 17 and 18 on both sides of the rail between the adjoining ends of the rails, 20 then shove the coupler clear back to the end of the rail, then lift one of the rails above the ball of the other and drop the said rail and raise the other rail so that the coupler can slip on over the flange of the 25 rail. Or it can be adjusted in another way. If an old rail is to be removed and a new one inserted in its place, shove the coupler on both ends of the new rail, lay the new rail, then raise the adjoining ends of the other 30 rails and drive the coupler up half way; then insert the wedges 12, then the wedge pins 14 and then the stop pins 17 and 18 and the cotters, and the parts are in position.

35 Modifications in detail may be resorted to without departing from the spirit of the invention or sacrificing any of its advantages.

What is claimed as new is:—

40 1. A coupler having flanges to embrace the base of a rail, and, upon one side, a chamber above the flange and to one side thereof, wedges inserted in said chamber and both bodily relatively movable therein, and pins

inserted between said wedges to spread them 45 in said chamber.

2. A coupler having flanges to engage the base of a rail, a chamber to receive wedges, wedges in said chamber and having grooves upon their adjacent faces, and pins inserted 50 in said grooves and having enlarged lower ends.

3. A coupler having flanges to engage the base of a rail and a chamber to receive wedges, wedges inserted endwise into said 55 chamber, means inserted between said wedges, and means interposed between adjacent ends of the rails and through said coupler to prevent creeping of the coupler except with the rail. 60

4. A coupler having a chamber to receive wedges, wedges in said chamber, means for spreading the wedges, and means interposed between the adjacent ends of the rails to force the coupler to creep with the rails. 65

5. A coupler having flanges to engage the base of a rail and a chamber to receive wedges with a horizontal portion to cover such wedges, wedges in said chamber beneath said horizontal portion, pins inserted 70 between the wedges, and means inserted between adjoining ends of the rails to compel the coupler to creep with the rails.

6. A coupler having flanges to engage the base of a rail and a chamber to receive 75 wedges with a flange to cover said wedges, wedges in said chamber, means inserted between said wedges, and means interposed between adjoining ends of rails, said last named means being passed through the 80 flange and base of the coupler.

In testimony whereof I affix my signature in presence of two witnesses.

WILLIAM M. HAVER.
